ATTORNEY

UNITED STATES PATENT OFFICE.

FRANK CALDWELL INGALLS, OF NEWARK, NEW JERSEY.

HEATING DEVICE.

1,295,509.

Specification of Letters Patent. Patented Feb. 25, 1919.

Application filed June 28, 1916. Serial No. 106,386.

To all whom it may concern:

Be it known that I, FRANK CALDWELL INGALLS, citizen of the United States of America, residing at 881 South 17th street, Newark, New Jersey, have invented a new and useful Heating Device; and I do hereby declare the following to be a full, clear, and exact description of the same.

This invention relates to new and useful improvements in air heating devices for use in connection with internal combustion engines.

The principal object of the invention is to provide an air heating device to be used as an attachment for internal combustion engines using gaseous fuel, and is adapted to be inserted anywhere in the intake line, and particularly in the hot air pipe which feeds the carbureter.

Another object of the invention is to provide a heating device of this nature, which occupies a minimum of space, thus leaving the pipe practically free for the passage of air therethrough, and also to provide for electrically controlling the operation of the device.

Another object of the invention is to provide a device which is simple and economical to construct, most efficient in use and quickly installed without particularly modifying any part of the engine.

To this end, the inventor has provided a heating device comprising an electrically heated conductor placed in a frame, and inserted in the hot air pipe and retained therein by suitable means, and has also provided a switch which may be manually brought into operative position, but which is automatically returned to an inoperative position after use.

In the drawings, which are for illustrative purposes only and, therefore, not drawn to any particular scale:

Figure 1 is an elevation of the hot air pipe with the heating device in position and showing the various connections thereto.

Fig. 2 is a horizontal sectional view, taken on the line 2-2 of Fig. 1, showing the switch when in inoperative position.

Fig. 3 is a similar view showing the switch in its operative position.

Fig. 4 is a sectional plan view, taken on the line 4-4 of Fig. 1, showing one form

of the heating device with means for retaining the same in position. 55

Fig. 5 is a sectional view showing another form of the device and the manner of retaining the same in position by the use of spring grips.

Fig. 6 is a view showing another similar 60 form of the device.

Referring now to Fig. 1, the hot air pipe 2, which may be placed close to the exhaust pipe of the engine to receive heat therefrom while the engine is running, is shown having a connection, 3, with the carbureter, 4, and carrying the switch, 5, to which is connected the insulated wire, 6, leading to a source of electric current (not shown), as, for instance, that which supplies the current for ignition purposes. 70

The switch 5, which is automatically held in an inoperative position and cannot be accidentally put into operative position, comprises an insulating block 7 supported on 75 the hot air pipe 2 by the yoke 8 (Fig. 2), or in any other desired manner, and provided with a longitudinally extending channel, 9, and two vertically disposed binding-posts 10 and 11 which extend through the 80 said channel. In this channel, between the binding-posts, a coiled spring 12 is provided having one end connected to one binding-post 10, and its other end connected to a cord 13 of insulating material, which cord 85 extends some distance out of the channel, and is provided with a handle or gripping means 14. To operate the switch, the operator simply grasps the handle of the cord, 13, and thereby pulls the end of the spring 12 90 into contact with the binding-post 11 (Fig. 3). On releasing the cord, the coiled spring withdraws out of contact with the binding-post 11, the switch thus becoming inoperative (Fig. 2). 95

As shown in Fig. 4, the heater comprises a metal frame 15 having U-shaped ends forming four transverse members 16, 17, 18 and 19. The members 16 and 19 carry coiled springs 20 and 21 to assist in maintaining the device in position within the pipe, and to aid in this result, the member 16 protrudes through the wall of the pipe 2 and is provided with a threaded end 22 on which a nut 23 and a jam-nut 24 are screwed. On the 100 member 17 an insulation 25 is provided, and

on this insulation is secured the exposed end portion of an insulated wire or cable 26, which connects the heating device with the switch 5. This exposed end of the cable 26 5 is connected, by a plurality of fine heating coils 27 to the members 18 and 19, thus grounding on the hot air pipe 2 and the engine.

In practice the heating coils are usually 10 heated above the ignition point of any vapor of the fuel that might be in the hot air pipe. To prevent any ignition of this vapor, the coils 27 are covered with a gas-tight envelop 27' of mica, asbestos or other suitable material, which holds the vapor from contact 15 with the hot coils.

If desired, the envelop may be omitted, as 20 in Figs. 5 and 6, and the resistance of the coils 27 made so great that the coils are never heated above the ignition point.

In the modification shown in Fig. 5, the frame 45 is shown provided with U-shaped end members, but here the device is shown maintained in position by spring grips 46 25 and 47 on the members 48 and 49.

In Fig. 6 the frame 55 is shown provided with two members 56 and 57 at one end with one member 58 at the other. The members 56 and 58 carry coiled springs 59 and 60, 30 which are arranged so as to engage opposite walls of the hot air pipe. The member 57 carries an insulating material 62, and around this insulation is secured the exposed end of the cable 26, and this exposed end is 35 connected to the coiled spring 60 on the member 58 by means of a plurality of fine heating coils 65.

The operation of the device is as follows:—

40 The electric current is carried from its source by the insulated wire 6 to the binding-post 10, thence to the coiled spring 12. When the cord 13 is pulled, contact is made with the binding-post 11, and the current 45 passes to the insulated wire or cable 26 and to the bare end thereof. From the bare end of the cable, the current passes to the heating coils and is then grounded on the walls of the pipe by connection with a member of 50 the frame.

Although this invention has many uses in connection with heating air, it is peculiarly adapted for use in connection with internal combustion engines. When an engine has 55 been at rest and it is desired to start the same, there being no exhaust to heat the air to be admitted to the carburetor, the question of warming such air has always been a serious one. However, with the use of the device 60 described and claimed herein, the long-standing lack of a heating device has been filled.

I claim as my invention:

1. A heating device comprising a frame 65 bent to form an intermediate member and

two end members; an insulation on the intermediate member; and heating wires carried by the insulation and one end member.

2. A heating device comprising a frame bent to form an intermediate member and 70 two end members; an insulation on the intermediate member; coiled springs on the end members; and heating wires carried by the insulation and one end member.

3. A heating device comprising a frame 71 bent to form an intermediate member and two end members one of which has a threaded end; a nut on said threaded end; an insulation on the intermediate member; and heating wires carried by the insulation and 80 one end member.

4. A heating device comprising a frame bent to form an intermediate member and two end members one of which has a threaded end; a nut on said threaded end; an insulation on the intermediate member; coiled springs on the end members; and heating wires carried by the insulation and one end member. 85

5. In a device as described, the combination 90 of a hot air pipe having a hole therein; a frame in the pipe comprising an intermediate member, and two end members; an insulation on said intermediate member; coiled springs on said end members and 95 engaging the sides of the pipe; and heating coils carried by said insulation and one of said end members.

6. In a device as described, the combination 100 of a hot air pipe having a hole therein; a frame in the pipe comprising an intermediate member and two end members one of which has an end protruding through said hole; a nut on said protruding end; an insulation on said intermediate member; coiled 10 end members; and heating coils carried by said insulation and one of said end members.

7. In a device as described, the combination 110 of a hot air pipe; a frame in said pipe and comprising three members, an insulation on one of the members; heating coils carried by one of the members and said insulation; and a conductor connected to the 11 said coils at the ends carried by the insulation.

8. In a device as described, the combination 120 of a hot air pipe; a frame in said pipe and comprising three members, one of which protrudes through the side of the pipe; a nut on the protruding end of said member; an insulation on one of the members; heating coils carried by one of the members and said insulation; and a conductor connected to the 12 said coils at the ends carried by the insulation.

9. In a device as described, the combination 130 of a hot air pipe; a frame in said pipe and bent to form an intermediate member 13

and two end members one of which protrudes through the side of the pipe; an insulation on the intermediate member; a conductor secured to said insulation; heating coils secured to said conductor and to one of the end members; and a nut on said protruding member.

10. In a device as described, a hot air pipe connected with a carbureter; a switch mounted on said hot air pipe and comprising the combination of an insulated block provided with a longitudinally extending channel and binding posts having their shanks extending through said channel; a coiled 15 spring in said channel between said binding posts and having one end connected to a binding post and its other end normally held in inoperative position, and means for bringing the free end into contact with the other 20 binding-post.

11. In a device as described, the combination of a hot air pipe connected with a carbureter and a metal frame yieldably supported therein; heating coils carried by said 25 frame; a switch mounted on said pipe and connected with a source of electric current; an insulated cable having one end connected to said switch and its other end bare of insulation and connected to said heating coils. 30 12. In a device as described, a hot air pipe connected to a carbureter and having an air heating device therein; a switch mounted on said pipe comprising an insulated block having notches therein; a channel open at one 35 end connecting said notches; binding-posts in said notches; a coiled spring in said channel between said binding-posts and having one end permanently in contact with one binding-post; means for bringing the other

end of said spring into contact with the 40 other binding-post, and means for connecting said switch and said heating device.

13. In a device as described, a hot air pipe having a switch connected to a source of electric current mounted thereon; an air 45 heating device in said pipe comprising a bar bent into a U-shape at each end forming outer and inner members; spring grips on the outer members engaging the walls of the pipe; an insulation on one inner member; an insulated cable having one end connected to the said switch and its other end bared and secured to the insulation on said member; heating coils connected at one end to the bared end of the cable and the other ends 50 connected with the spring grip on one outer member. 55

14. In a device as described, a hot air pipe; a heating device entirely within said pipe and comprising a frame having U- 60 shaped ends forming outer and inner members; coiled springs on the outer members and an insulation on one inner member; a conductor mounted on said insulation and heating coils secured to said conductor and 65 to the other inner member.

15. In a device as described, a hot air pipe connected with a carbureter; and a heating means disposed between the inlet of the pipe and the carbureter. 70

16. A heater comprising a frame having members; heating coils carried on said members and means for connecting said coils to a source of electric current.

In testimony whereof, I have signed my 75 name to this specification.

FRANK CALDWELL INGALLS.
